CLAIM

The ornamental design for a propeller lock for marine engine, as shown and described.

DESCRIPTION

FIG. 1 is an assembled perspective view of the propeller lock for marine engine according to the present invention.

FIG. 2 is an exploded perspective view of the propeller lock for marine engine according to the present invention.

FIG. 3 is a front view of the propeller lock for marine engine according to the present invention.

FIG. 4 is a top view of the propeller lock for marine engine according to the present invention.

FIG. 5 is a left side view of the propeller lock for marine engine according to the present invention.

FIG. 6 is a rear view of the propeller lock for marine engine according to the present invention.

FIG. 7 is a right side view of the propeller lock for marine engine according to the present invention; and,

FIG. 8 is a bottom view of the propeller lock for marine engine according to the present invention.

The broken lines in all views are for illustrative purposes only and form no part of the claimed design.
